UNITED STATES PATENT OFFICE.

SHERMAN C. ABRAMSON, OF ENGLEWOOD, NEW JERSEY, ASSIGNOR TO
HUGO L. HILLER, OF NEW YORK, N. Y.

LACING.

No. 818,991.

Specification of Letters Patent.

Patented April 24, 1906.

Application filed June 22, 1905. Serial No. 266,371.

To all whom it may concern:

Be it known that I, SHERMAN C. ABRAMSON, a citizen of the United States, and a resident of Englewood, in the county of Bergen 5 and State of New Jersey, have invented a new and useful Improvement in Lacings, of which the following is a specification.

The object of this invention is to provide a flat lacing with a transverse tip whereby 10 the lacing is prevented from being unintentionally withdrawn after it has been inserted through the eyelets of the article in connection with which it is used, and in which the 15 end of the lacing is prevented from fraying out and in which the lacing is caused to present a very handsome and neat appearance.

In the accompanying drawings, Figure 1 represents in perspective a flat lacing having 20 my improved tips thereon, a portion of the lacing intermediate its ends being broken away. Fig. 2 is a detail view showing the metallic stiffening-piece and one end of the lacing in connection with which the piece is interlocked to form the transverse tip, and Fig. 3 is an 25 exaggerated transverse section through the tip to show one way of interlocking the stiffening-piece with the body of the lacing.

The flat lacing is denoted as a whole by 1. Transverse tips 2 are provided at the ends of 30 the lacing, which tips extend the full width of the body of the lacing and in the present instance are formed as follows: A stiffening-piece 3 is provided which may consist of sheet metal of the desired shape and size, which 35 stiffening-piece is arranged to be interlocked with the end of the body of the lacing—as, for instance, by folding the stiffening-piece and lacing together to form a substantially round tip, as shown in Fig. 3.

To insert the lacing through an eyelet, the 40 body of the lacing adjacent to the tip may be crushed around the tip to bring the same into a substantially longitudinal position. After the lacing has been inserted through the eyelet it may be flattened out, thus bringing the 45 tip again into its position transverse to the lacing.

It will be seen that a lacing provided with a transverse tip, as above described, may be readily inserted through an eyelet and after 50 it has been inserted therethrough cannot be withdrawn unintentionally. Furthermore, it will also be seen that a very thin tip can be used, so that at a short distance it is scarcely perceptible. It may thus be used in connection with lacings for people who wish to wear 55 lacings without tips and who have usually cut off the tips after the lacing has been passed through the eyelets. It will furthermore be seen that this tip prevents the lacing 60 from fraying at its end, thus causing the lacing to retain an attractive appearance at all times.

What I claim is—

A flat lacing having at its end a transversely - disposed stiffening - piece permanently secured to the body of the lacing, the said stiffening-piece serving to hold the lacing laterally distended.

In testimony that I claim the foregoing as 70 my invention I have signed my name, in presence of two witnesses, this 20th day of June, 1905.

SHERMAN C. ABRAMSON.
